United States Patent

Des. 237,817
Patented Nov. 25, 1975

237,817

PENDANT

James L. Foreman, 801 Alamanda,
Boca Raton, Fla. 33432

Filed June 27, 1973, Ser. No. 374,006

Term of patent 14 years

Int. Cl. D11—01

U.S. Cl. D45—17

FIG. 2

FIG. 1

FIG. 1 is a front elevational view of a pendant showing my new design; and

FIG. 2 is a side elevational view thereof.

The back of my pendant is identical with the front as shown in FIG. 1.

I claim:

The ornamental design for a pendant, as shown and described.
